UNITED STATES PATENT OFFICE

146,914

DESIGN FOR A COMBINATION SHOE POLISHING KIT

Bernard A. Grae, Chicago, Ill.

Application April 22, 1946, Serial No. 128,847

Term of patent 7 years

(Cl. D9—2)

To all whom it may concern:

Be it known that I, Bernard A. Grae, a citizen of the United States and resident of Chicago, in the county of Cook and State of Illinois, have invented a new, original, and ornamental Design for a Combination Shoe Polishing Kit, of which the following is a specification, reference being had to the accompanying drawing, forming a part thereof.

Figure 1 is a perspective view of a combination shoe polishing kit, showing my new design; Figure 2 is a side elevational view; and Figure 3 is a bottom plan view thereof.

I claim:

The ornamental design for a combination shoe polishing kit, as shown.

BERNARD A. GRAE.
